UNITED STATES PATENT OFFICE

166,864

GAMBREL

Philip C. Mecum, Haywood, Calif.

Application June 18, 1951, Serial No. 15,589

Term of patent 3½ years

(Cl. D11—1)

To all whom it may concern:

Be it known that I, Philip C. Mecum, a citizen of the United States, residing at Hayward, Alameda County, State of California, have invented a new, original, and ornamental Design for a Gambrel, of which the following is a specification, reference being had to the accompanying drawing, forming a part hereof, wherein,

Figures 2 and 3 are plan and side views respectively of the gambrel.

I claim:

The ornamental design for a gambrel, substantially as shown.

PHILIP C. MECUM.
